JOHN IRVING NASMITH, OF ELTHAM, LONDON, AND CHRISTOPHER BRUNSWICK CHICKEN, OF BEXLEY HEATH, ENGLAND, ASSIGNORS TO VICKERS-ARMSTRONG LIMITED, OF WESTMINSTER, ENGLAND

MECHANISM FOR RAISING FEED AND OTHER TABLES OR PLATFORMS

Application filed October 23, 1928, Serial No. 314,436, and in Great Britain August 31, 1928.

This invention relates to mechanism for raising feed and other tables or platforms and has particular reference to mechanism for raising the feed tables of sheet feeding apparatus of the type in which a pile of sheets or cards is supported by the table, and the latter is progressively raised as the pile diminishes due to the successive feeding of the top sheets. In conjunction with sheet feeding apparatus of this type it has been proposed to support the feed table by levers operable on the "lazy tongs" principle from an operating member consisting of a toothed rack movable longitudinally in a horizontal direction by worm gearing and connected to the lower end of one of the said levers. This arrangement possesses certain drawbacks since the mechanical advantage is very adverse when the load is heaviest and the speed of the table as it rises, or the amount by which the table rises with a unit movement of the operating member, varies considerably between the initial and final positions of the table. The object of the present invention is to overcome these drawbacks by controlling the amount by which the table rises when the operating member is actuated.

According to the invention the table raising mechanism comprises an operating member adapted to impart vertical movement to the table through the medium of levers operable on the "lazy tongs" principle and means for modifying or changing the normal character of movement of the said levers so that a predetermined movement is imparted to the table. The lower ends of the levers are mounted so as to permit one to approach the other as the angles between the levers are varied and the table is raised. The movement modifying means may comprise an inclined prop or strut the lower end of which is movable along a stationary cam surface and the upper end of which may be connected to one or both of the levers but is preferably connected to the central pivot of such levers.

The operating member may comprise a rod or toothed rack movable longitudinally in a horizontal or substantially horizontal path and having one end thereof connected to the lower end of the said prop or strut. The cam surface is shaped so that the prop or strut operating in conjunction with the said levers is caused to impart a predetermined movement (which may be varied by varying the shape of the cam) to the table and by suitably forming this surface equal increments of movement of the operating member may produce equal or substantially equal increments of movement of the table. In some cases the stationary cam surface may be substituted by a movable cam plate pivotally mounted on the central pivot of the "lazy tongs" levers and co-operating with a stationary roller, said cam receiving its motion from the said operating member.

In order that the said invention may be clearly understood and readily carried into effect, the same will now be described more fully with reference to the accompanying drawings, in which:

Figure 1 is a side elevation of a table raising mechanism embodying the invention, and

Figure 2 is a part plan of the mechanism illustrated in Figure 1.

Figures 3 and 4 are views similar to Figures 1 and 2 showing a modification.

In Figures 1 and 2 *a* is the operating member consisting of a substantially horizontal rod formed with teeth *b* to enable it to be moved longitudinally by a pinion *c*. *d* is the feed table movable in a vertical direction. *f*, *f'* are the levers operable on the "lazy tongs" principle, there being two sets of such levers disposed on opposite sides of the feed table. The lower end of the lever *f* is pivotally mounted in a fixed support *g* and the lower end of the other lever *f'* is pivotally connected by a pin *h* to a block *i* which is slidably mounted on a horizontal bar *j* supported at its ends in a pair of blocks *k*. The upper end

of lever f is similarly connected by a pin to a block l slidably mounted on a horizontal bar m supported from the lower surface of the feed table and the upper end of the lever f^1 is pivotally connected to a lug n which is secured to or formed integral with the feed table. The levers on the opposite side of the feed table are arranged and mounted in a similar manner and the central pivot of one set of levers is connected to that of the other set by a transverse shaft o .

p is the stationary cam surface made up of two tracks which are formed at the upper parts of a pair of spaced vertically disposed plates q held in their appropriate relative positions by transverse bolts r . s is the inclined prop or strut which is interposed between the shaft o and the cam surface p and in order to facilitate its movement over the cam surface the lower end of the prop is pivotally connected to a pin t which is provided with a pair of spaced rollers u , the spacing of the rollers corresponding with that of the plates q . The end of the operating member a is also secured to the pin t and it will be evident that when the operating member is moved to the left in Figure 1 the rollers u will be caused to travel along the cam tracks and thus cause the upward movement of the transverse shaft o with the result that the angles between the levers f and f^1 will be varied and the feed table d raised. In Figures 3 and 4 the operating member is indicated at a^1 . As in the previous arrangement the operating member is formed with teeth b^1 to enable it to be moved longitudinally by a pinion c^1 . d^1 is the feed table and f^2, f^3 are the levers operable on the "lazy tongs" principle, the lower end of the lever f^2 being pivotally mounted in a fixed support g^1 and the lower end of the other lever f^3 being pivotally connected by a pin h^1 to a block i^1 which is slidably mounted on a horizontal bar j^1 supported at its ends in a pair of fixed blocks k^1 . The upper end of the lever f^2 is similarly connected by a pin to a block i^2 slidably mounted on a horizontal bar m^1 supported from the lower surface of the feed table and the upper end of the lever f^3 is pivotally connected to a lug n^1 secured to or formed integral with the feed table. Another pair of "lazy tongs" levers are arranged and mounted in a similar manner on the opposite side of the feed table and the central pivot of one set of levers is connected to that of the other set by a transverse shaft o^1 . In this instance, instead of employing stationary cam tracks as in the arrangement shown in Figures 1 and 2, a movable cam plate q^1 is pivotally mounted upon the transverse shaft o^1 and connected at a^2 to the operating member a^1 the active surface of the pivoted cam plate q^1 bearing against a stationary roller v mounted on the frame of the machine. Movement of the said operating member a^1 will cause the pivoted cam to co-oper-

ate with the roller v and raise the feed table d as in the arrangement already described. In the examples shown, the cam tracks or the pivoted cam are shaped in such a manner that equal increments of movement of the operating member are caused to produce equal or substantially equal increments of movement of the table so that the mechanical advantage of the arrangement is substantially constant and the movement of the table rendered more uniform.

What we claim and desire to secure by Letters Patent of the United States is:—

1. Mechanism for raising feed and other tables comprising table supporting levers operable on the "lazy-tongs" principle, an operating member and means for modifying the normal character of movement of the levers so that a predetermined movement is imparted to the table.

2. Mechanism for raising feed and other tables comprising table supporting levers operable on the "lazy-tongs" principle, an operating member, and means associated with the levers for equalizing the upward increments of movement of the table resulting from equal increments of movement of the operating member.

3. Mechanism for raising feed and other tables comprising table supporting levers operable on the "lazy-tongs" principle, an operating member for varying the angles between the levers and means interposed between the levers and the operating member for controlling the amount by which the table is moved upon actuation of the operating member.

4. Mechanism for raising feed and other tables comprising table supporting levers operable on the "lazy-tongs" principle, an operating member movable in a horizontal path and means whereby equal increments of movement of the operating member produce equal increments of movement of the table.

5. Mechanism for raising feed and other tables comprising table supporting levers operable on the "lazy-tongs" principle, a cam plate having its cam surface facing upwardly, an inclined prop having its upper end connected to one of the levers and its lower end movable over the cam surface and means for causing the lower end of the prop to move along the cam surface.

6. Mechanism for raising feed and other tables comprising pivotally connected table supporting levers operable on the "lazy-tongs" principle, a vertically disposed cam plate having a cam surface formed at the upper end thereof, an inclined prop having its upper end connected to the central pivot of the levers and its lower end resting on the cam surface and an operating member for causing the lower end of the prop to move along the cam surface.

7. Mechanism for raising feed and other
tables comprising table supporting levers
operable on the "lazy-tongs" principle and
means for causing the lower ends of the le-
vers to approach one another, the said means
comprising a cam plate and an inclined prop
having its upper end connected to one of the
levers and its lower end movable along the
cam plate.
